[57] CLAIM

The ornamental design for a battery compartment, as shown and described.

DESCRIPTION

FIG. 1 is a plan view showing my new design of a battery compartment, with the illustrative side rails being shown in dashed lines and forming no part of the claimed invention.

FIG. 2 is a front view of the design shown in FIG. 1.

FIG. 3 is a rear view of the design shown in FIG. 1.

FIG. 4 is a bottom view of the design shown in FIG. 1.

FIG. 5 is a right side view of the design shown in FIG. 1.

FIG. 6 is a left side view of the design shown in FIG. 1.

FIG. 7 is a perspective view of the design shown in FIG. 1; and,

FIG. 8 is a perspective view of the design shown in FIG. 1, and prior to its insertion into the illustrative smart card reader, which is indicated in dashed lines and forms no part of the claimed invention.
